CARBURETER.

1,287,467.

Specification of Letters Patent. Patented Dec. 10, 1918.

Application filed January 30, 1917. Serial No. 145,474.

To all whom it may concern:

Be it known, that I, ARTHUR H. SEAMAN, a citizen of the United States, residing at Seattle, in the county of King and State of Washington, have invented certain new and useful Improvements in Carbureters; and I do hereby declare the following to be a full, clear, and exact description of the invention, such as will enable others skilled in the art to which it appertains to make and use the same.

This invention relates to apparatus for generating a combustible mixture or vapor for internal combustion engines and other purposes, and has for its object to provide

for the more thorough and rapid mixture of a hydrocarbon fuel with air.

A further object of the invention is to provide a carbureter of such construction as to eliminate complex mechanical structures and delicate operating parts and float valves, and thereby to provide a simple, practicable and economical carbureter.

With these and other objects in view the present invention consists of a means for supplying liquid fuel to a chamber or cylinder in the presence of air and means for attenuating the laden air so as to cause the intimate mixture of the vapor of the fuel with the air and then to subsequently discharge the enriched mixture into a distributor for consumption in a combustion motor or other apparatus.

One embodiment of my invention is described in the following specification and illustrated in the accompanying drawing, in which:

Figure 1 is a vertical central section through the carbureter with its fuel supply connections shown diagrammatically, and

Fig. 2 is a plan view of the cylinder of the apparatus.

My present invention is designed with the object of simplifying the construction of carbureters and providing for the more thorough mixture of the liquid fuel with a charge of air which is to be delivered to a combustion engine or other apparatus in which the enriched fuel may be utilized, and in the present organization of the carbureter there is provided a suitably sized cylinder 2 in which there is operable a piston 3 connected to a connecting rod 4 which in turn is connected to a crank 5 on a pump shaft 6, for instance as shown, this latter be-

ing operative by any suitable driving connections with the motor with which the carbureter may be used or which may be driven from any other suitable source of power. The upper end or head of the cylinder 2 is shown as provided with a valve seat 10 above which there is connected a mixing or distributing chamber 11, one end of which is adapted to be connected in any suitable manner to an engine, a part of which is illustrated at 12, or may be connected to any other apparatus to which it is desired to deliver the enriched vapor.

One of the features of the present invention is to provide for the induction of a charge of hydrocarbon fuel into the cylinder 2 in which, by the operation of the piston 3, a charge of air above the latter which has been enriched by the hydrocarbon admitted to the cylinder, will be attenuated or rarefied by the production of a partial vacuum within the cylinder 2, the effect of which will be to cause the vapor particles of the fuel to become more intimately associated with the constituent elements of the air while the latter is rarefied, and the further effect of which will be to increase the rapidity of the evaporation or dissolution of the moist particles of fuel which may be contained within the cylinder 2 above the piston 3. For the purpose of thus introducing a charge of vapor into the cylinder above the piston 3, suitable fuel supply means are provided, which, in the present instance, are indicated as including supply tube 13, from which lead connecting pipes 15 attached to the head 9 and having suitable control valves 14. While the fuel may be admitted to the cylinder 2 at any suitable point therein through means of the supply pipes 15, preferably the inlet openings from the supply tubes or pipes 15 are disposed so as to open into the seat 10 of the head 9 and are adapted to be closed normally during the suction stroke of the piston 3 by an automatic valve 16 having its face formed the counterpart of the seat 10, and which is adapted to be seated by a spring 17 surrounding an upwardly extending stem 18 of the valve which is guided in its movement through a suitable yoke or standard 19.

For the admission of air into the cylinder 2, the mixing chamber or distributor 11, which is mounted on the head 9 of the cylinder, is shown as provided with one or more

air inlet apertures 11^a which may be controlled by a suitable valve structure 11^b if desired which may be operated to cover or uncover the air inlet openings 11^a to the desired extent and thereby regulate the amount of air drawn into the distributing chamber 11 through which the enriched vapors are carried to the engine or other consuming apparatus.

- 10 The operation of this device is substantially as follows: Power being transmitted to the shaft 6 through any suitable connection, the piston 3 is then reciprocated in the cylinder 2 and on its upward stroke will displace air from within the cylinder, thus raising the valve 16 from its seat 10, allowing the expelled air to pass into the distributing chamber or mixer 11, and as this air passes the face of the valve seat 10 the inlet openings in the supply tubes 15 being uncovered by the lifted valve 16, there will be induced through the tubes 15 a supply of fuel which will be sprayed into the port 10 and sprayed upwardly by the upward inclination of the ends of the ducts in the head 9 against the face of the valve 16, the atomizer fuel entering the chamber 2 through the open port or seat 10 and thus enriching the air within the cylinder above the piston 3 when the latter is in its upper position. Upon equalization of pressure flowing out through the port or seat 10 with the tension or resistance of the spring 17, the valve 16 will be seated, thus covering the mouths of the ports from the tubes 15 and then upon the downward stroke of the piston 3 the included air within the cylinder 2 will be attenuated or rarefied, thus causing a thorough commingling of the vapor particles with the air constituents, and the tendency of the formation of the vacuum permitting the more rapid evaporation of the particles of the vapor and a subsequent expansion of the gas produced by the evaporation of the vapor. Thereafter on the upward stroke of the piston 3 the expanded vapor and enriched air will be compressed and expelled through the port or seat 10 against the valve 16 and across the faces of the ducts connecting with the inlet tubes 15.

As the enriched mixture from the cylinder 2 passes into the mixing chamber or distributor 11 it is further mixed with an incoming charge of air through the air inlet ports 11^a, and the enriched vapor is then drawn through the distributing chamber 11 to a suitable point of distribution, for instance at the engine 12.

It is understood that when a multiple-cylinder engine is utilized, the delivery chamber 11 may be attached to a suitable manifold for distributing the enriched vapor to each of the cylinders of the engine, and it will be further understood that as many of the carburetors may be utilized as may be

necessary to supply the proper quantity and quality of vapor to the engine. The speed of reciprocation of the piston 3 may be determined according to the size of the engine and the number of its cylinders so that there will be a substantially constant supply of enriched vapor from the cylinder head and into the mixing chamber 11. It is understood that various modifications, alterations and variations of the structure may be resorted to within the limits of my present invention and within the scope of the appended claims.

What is claimed as new is:

1. A carbureter comprising a vacuum pump having a port at the outer end of the cylinder for induction and eduction of air, an outwardly opening valve yieldingly seating over the port, and means for supplying liquid to the pump at said port to be mixed with the passing air.

2. A carbureter comprising a vacuum pump having a port at the outer end of the cylinder for the inlet and outlet of air, means for supplying liquid fuel to the pump at the port, and a yielding valve controlling inlet and outlet of air and liquid fuel through the port.

3. A carbureter comprising a distributing chamber having air inlet means, a vacuum pump having a single inlet and outlet port leading to the chamber, an automatic outwardly opening valve for the port, and means for supplying liquid fuel to the pump, which liquid fuel is mixed with the expanded and compressed air and returned to the chamber.

4. A carbureter having a delivery connection and air inlet means, a cylinder attached thereto having a port communicating with the chamber, a valve for the outlet of air from the cylinder, means for supplying liquid fuel through the port, and a piston for attenuating and compressing the air in the presence of the fuel and returning it through said port to the chamber.

5. A carbureter having a chamber with air inlet means, a pump having a port for the intake and discharge of air, a valve for controlling the flow of air, fuel supply means for introducing liquid fuel under control of the valve, said pump operating for attenuating a charge of enriched air and then discharging the mixture into said chamber past the valve and supplying means.

6. A carbureter having a delivery chamber with air inlet means, a cylinder having a port, a valve for the port, means for supplying liquid fuel to the cylinder through the port, and a piston operating in the cylinder to attenuate the air in the chamber and then discharge it through said port, fuel being sprayed as the outgoing air passes the valved port, and enriching the air closed in the cylinder.

7. A carbureting device comprising a delivery chamber with air inlet means, a cylinder connected thereto by a valved port for the admission and eduction of air, a piston operative therein, to attenuate and expel air through the port, and means for supplying liquid fuel at the valve port, whereby when the valve and piston are operating the fuel is intimately mixed with the air passing through the port.

8. A carbureting device comprising a delivery chamber with air inlet means, a cylinder

connected thereto by a valved inlet and outlet port, a piston operative therein, to attenuate and expel air through the port, and means for supplying liquid fuel to the valve seat, the piston on one stroke compressing air below the valve until it is lifted, whereupon there is an induced flow of liquid from said means as the air passes out, the valve of the port opening outwardly and held yieldingly to its seat.

In testimony whereof I affix my signature.

ARTHUR H. SEAMAN.
